CLAIM

The ornamental design for a covered pitcher or the like, as shown and described.

DESCRIPTION

FIG. 1 is a top perspective view of the covered pitcher or the like showing our new design;

FIG. 2 is a right side elevational view thereof, the side opposite being a mirror image;

FIG. 3 is a top plan view thereof;

FIG. 4 is a front elevational view thereof;

FIG. 5 is a rear elevational view thereof;

FIG. 6 is a bottom plan view thereof; and

FIG. 7 is a cross-sectional view taken along line 7—7 of FIG. 3.
